US0D1076290S

(12) **United States Design Patent** (10) **Patent No.:** **US D1,076,290 S**
(45) **Date of Patent:** **** May 20, 2025**

(54) **BLOWER**

(71) Applicant: **Shenzhen Keying Technology Co., Ltd.**, Shenzhen (CN)

(72) Inventor: **Tenghui Ye**, Shenzhen (CN)

(73) Assignee: **Shenzhen Keying Technology Co., Ltd.**, Shenzhen (CN)

(**) Term: **15 Years**

(21) Appl. No.: **29/964,988**

(22) Filed: **Sep. 25, 2024**

(51) LOC (15) Cl. **15-05**

(52) U.S. Cl.

USPC **D32/15**

(58) **Field of Classification Search**

USPC D32/15, 17; D23/383

CPC A01G 20/47; E01H 1/0809

See application file for complete search history.

Primary Examiner — Kimberly Barnes

(74) Attorney, Agent, or Firm — Nitin Kaushik

(57) **CLAIM**

The ornamental design for a blower, as shown and described.

DESCRIPTION

FIG. 1 is a front perspective view of a blower, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the blower, which form no part of the claimed design.

1 Claim, 8 Drawing Sheets
